ROCK DRILL

Elmer G. Gartin, Claremont, N. H., assignor to
Sullivan Machinery Company, a corporation of
Massachusetts

Application September 19, 1941, Serial No. 411,524

18 Claims. (Cl. 255—51)

This invention relates to rock drills, and more particularly to improvements in a drill steel guide for a hammer rock drill.

An object of the present invention is to provide an improved drill steel guide. Another object is to provide an improved drill steel guide having novel means for locking the guiding elements thereof in guiding position, and wherein the locking means is releasable by engagement of the drill hammer motor therewith. A further object is to provide an improved drill steel guide of the pivoted arm type having improved pivotal mounting means for the guide arms and improved locking means individual to each arm whereby the arms may be locked separately or both arms may be locked concurrently in guiding relation with a drill steel. A still further object is to provide an improved drill steel guide having individual locking means for the guiding elements thereof. Yet another object is to provide a novel mounting structure for the guiding elements of a drill steel guide. A still further object is to provide novel latching means for the guide arms for locking the latter in steel guiding position and releasable automatically by direct engagement of the drill hammer motor therewith as the latter is fed forwardly along the guideways of its supporting guide. These and other objects and advantages of the invention will, however, hereinafter more fully appear in the course of the ensuing description and as more particularly pointed out in the appended claims.

In the accompanying drawings there are shown for purposes of illustration several forms which the invention may assume in practice.

In these drawings:

Fig. 1 is a fragmentary plan view of a hammer rock drill with which an embodiment of the improved drill steel guide is associated.

Fig. 2 is a side elevational view of the rock drill and steel guide shown in Fig. 1, parts being shown in vertical section to illustrate details of construction.

Fig. 3 is a cross sectional view taken substantially on line 3—3 of Fig. 2, showing the guide arms in steel guiding position.

Fig. 4 is a view similar to Fig. 3, showing the guide arms in their released non-guiding position.

Fig. 5 is a cross sectional view taken substantially on line 5—5 of Fig. 2.

Fig. 6 is a detail cross sectional view taken substantially on line 6—6 of Fig. 2.

Fig. 7 is a view in longitudinal vertical section taken substantially on line 7—7 of Fig. 3.

Fig. 8 is a fragmentary plan view of a rock drill

with which another embodiment of the improved drill steel guide is associated.

Fig. 9 is a side elevational view, with parts shown in vertical section, of the rock drill and steel guide shown in Fig. 8.

Fig. 10 is a front end elevational view of the rock drill and steel guide shown in Figs. 8 and 9, with the guide arms in steel guiding position.

Fig. 11 is a detail cross sectional view taken substantially on line 11—11 of Fig. 9.

Fig. 12 is a horizontal sectional view taken substantially on line 12—12 of Fig. 10.

Fig. 13 is a side elevational view similar to Fig. 9, showing still another embodiment of the invention.

Fig. 14 is a detail cross sectional view taken substantially on line 14—14 of Fig. 13.

Fig. 15 is a horizontal sectional view taken substantially on line 15—15 of Fig. 13.

In the several illustrative embodiments of the invention the improved drill steel guide is shown associated with a conventional hammer rock drill of the mounted drifter type. However, it will be evident that the improved drill steel guide may be associated with other types of drills if desired.

The hammer rock drill disclosed herein comprises a conventional drill hammer motor 1 slidably guided on a conventional guide shell 2, the latter adapted to be mounted on a conventional drill support. The hammer motor comprises a motor cylinder 3 containing a reciprocating hammer piston (not shown) for percussively actuating a drill steel 4, the latter being supported in a usual chuck within a front chuck housing 5 suitably attached to the front end of the motor cylinder. The hammer motor cylinder has lateral guides 6, 6 slidably received within longitudinal guideways 7, 7 of the guide shell. The hammer motor may be fed along the shell guideways by means of a conventional feed screw engaged with a feed nut carried by the motor cylinder, so that when the screw is rotated the motor is fed longitudinally relative to the shell. Since, as above stated, the rock drill is of a conventional design and is well known to those skilled in the art, further description and illustration thereof are unnecessary.

In the embodiment of the invention shown in Figs. 1 to 7, inclusive, the improved drill steel guide, generally designated 8, comprises front and rear transverse plates 9 and 10 attached, by bolts 11, herein three in number, to the front end of the guide shell and held in spaced parallel relation by spacing sleeves 12 interposed between the plates and surrounding the bolts. The rear plate 10 has an integral bearing boss 13 in which

the forward bearing portion 14 of the feed screw is journaled. Pivots mounted on the spacing sleeves on the upper bolts is a pair of cooperating guide arms 15, 15 having guiding portions 16 appropriately shaped to engage the drill steel. The rear plate 10 is cut away at 17 at its opposite sides so that the lateral guides 6 of the hammer motor may move forwardly relative to the rear plate when the guide arms are in their released non-guiding position. The guide arms 15 are adapted to embrace the body of the drill steel to hold the latter centered during starting or "spotting" of a hole, in the manner well known to those skilled in the art. As illustrated, the hubs of the guide arms 15 are arranged between the front and rear plates, and depending from the arm hubs are armlike lugs 18 to which the ends of a coiled torsion spring 19 are connected. This torsion spring encircles the spacing sleeve on the lower bolt intermediate the arm pivot axes, in the manner shown, and the ends of the spring are secured to the arm lugs by pins 20 fitted within openings in the lugs. This torsion spring constantly urges the guide arms 15 toward their wide open released position, and when the guide arms are in released position abutment surfaces 21 on the arm lugs engage corresponding surfaces 22 on the rear plate to limit outward swinging movement of the arms. The abutment surfaces on the arms and plate are held in yielding abutting engagement by the torsion spring. Formed in the guide arms respectively are bores 23 herein arranged in parallelism with the arm pivots, and respectively mounted in these bores are reciprocable plunger locks 24. These locks have cylindric body portions 25 fitted within the arm bores, and the locks are constantly urged toward their rearmost position by coil springs 26. The side walls of the bores are preferably slotted at 27 for a portion of their length, and the cylindric lock bodies have depending lock portions projecting downwardly through these slots, and these locking portions are received in longitudinal slots 29 in the rear plate 10 when the locking plungers are in their rearward position, thereby to lock the guide arms in their steel guiding position as shown in Fig. 3. Engagement of the locking portions 28 with the sides of the arm slots 27 prevents rotation of the locking plungers in the arm bores. The locking plungers are maintained against endwise displacement from the arm portions by engagement of the locking portions 28 with the rear plate, and as the arms are swung about their pivots these locking portions slide over the front surface of the rear plate. The springs acting on the locking plungers hold the locking portions in frictional contact with the rear plate, so that the arms are yieldingly held in their wide open non-guiding position. The cylindric body portions 24 of the locking plungers extend rearwardly from the rear surfaces of the guide arms into a position to be engaged by the front chuck housing 5 of the drill hammer motor, as hereinafter explained.

In the operation of this embodiment of the improved drill steel guide when it is desired to start or "spot" a drill hole the guide arms may be swung about their pivots into the position shown in Fig. 3 with their guiding portions 16 in engagement with the drill steel 4, and as the arms are swung together the locking portions 28 of the plunger locks snap within the locking slots 29 in the rear plate to lock the guide arms in steel guiding position. As the drill hammer mo-

tor is fed forwardly along the shell guideways the front chuck housing 5 engages the projecting rear ends of the locking plungers and shoves the latter forwardly in the arm bores 23 to effect release of the locking portions 28 from the plate slots. When the arm locks are released the torsion spring 19 acts automatically to swing the guide arms into their wide open non-guiding position shown in Fig. 4, so that the hammer motor can move forwardly between the arms without interference therewith. As the arms swing outwardly about their pivots, the locking portions 28 slide over the front surface of the rear plate so that when the arms are in their wide open position they are frictionally held in such position by the action of the coil springs 26. By the provision of the individual locks for the guide arms the latter may be separately placed in guiding relation with the drill steel, for instance, during "spotting" of a hole on an inclined face when but a single arm is sufficient to prevent lateral deflection of the drill steel.

In the embodiment of the invention shown in Figs. 8 to 12, inclusive, the guide arms, their pivotal mountings and the particular torsion spring arrangement are similar to those described above. In this instance, a latch 35 is pivotally mounted on a pivot pin 36 arranged transversely of and supported by the front plate and has rearwardly projecting locking lugs 37, 37 engageable with locking projections 38 on the guide arms. Pins 39 are reciprocably guided in bores 40 in the guide arms, and these pins are engageable with the latch and have their rearward end portions projecting rearwardly from the guide arms in a position to be engaged by the front chuck housing of the drill hammer motor. A spring-pressed plunger 41 on the front plate frictionally engages the hub of the pivoted latch to hold the latter in position. Pins 42 secured to the arms are received within elongated slots 43 in the pins for limiting sliding movement of the pins in the arm bores. As in the manner of the embodiment of the invention described above, as the drill hammer motor is fed forwardly along the shell guideways the front chuck housing engages the projecting rear ends of the pins 39 and shoves the latter forwardly in the arm bores to effect release of the latch from the locking projections on the arms; and when the latch is released the torsion spring acts automatically to swing the guide arms into their wide open non-guiding position, so that the hammer motor can move forwardly between the arms without interference therewith. As in the form of the invention above described, the guide arms may be separately locked in guiding relation with the drill steel so that at times but a single arm may serve as a guide.

In the embodiment of the invention shown in Figs. 13 to 15, inclusive, the guide structure is similar to that shown in Figs. 1 to 7, inclusive. In this construction, however, cylinder locking plungers 45 are arranged within bores 46 in the guide arms and coil springs 47 urge the locking plungers rearwardly. The locking plungers project rearwardly from the rear surfaces of the guide arms and are notched at 48 to receive projections 49 on the rear plate. Pins 50 secured to the guide arms are received in elongated slots 51 on the plunger locks for holding the latter against rotation within the arm bores. Engagement of the rear ends of the plunger locks with the rear plate prevents axial displacement of

the locks from the arm bores, and the locks by their frictional contact with the plates hold the guide arms in their released non-guiding position. As the drill hammer motor is fed forwardly along the shell guides the front chuck housing engages the projecting ends of the locking plungers and shoves the latter rearwardly in the arm bores to release the plungers from the plate projections 49; and, as in the forms of the invention above described, the arms are automatically swung outwardly into their non-guiding position by the torsion spring when the arm locks are released. Likewise as in the forms above described, by the provision of the individual arm locks the guide arms may be placed either separately or concurrently in guiding relation with the drill steel.

As a result of this invention an improved drill steel guide is provided which is rugged in construction and relatively simple in design. It will also be evident that by mounting the guide arms in the manner shown and by the provision of the individual locking means for the arms, the latter may be either separately or concurrently locked in guiding relation with the drill steel. Further, by the provision of the particular locking arrangement, the guide arms are automatically released from the steel upon engagement of the front chuck housing of the hammer motor with the locking devices. Other uses and advantages of the invention will be clearly apparent to those skilled in the art.

While there are in this application specifically described several forms which the invention may assume in practice, it will be understood that these forms of the same are shown for purposes of illustration and that the invention may be modified and embodied in various other forms without departing from its spirit or the scope of the appended claims.

What I claim as new and desire to secure by Letters Patent is:

1. In a drill steel guide, a support, guiding elements mounted on said support for movement into and out of steel guiding position, locking means mounted on and movable into locking position relative to said guiding elements and engageable with said support for connecting said elements to said support to hold said elements in steel guiding position, said guiding elements being movable separately or concurrently into guiding relation with a drill steel, and said locking means serving to hold either or both of said elements in such position.

2. In a drill steel guide, a support, guiding elements mounted on said support for movement into and out of steel guiding position, locking means movable relative to said guiding elements for connecting said elements to said support to hold said elements in steel guiding position, said guiding elements being movable separately or concurrently into guiding relation with a drill steel, and said locking means serving to hold either or both of said elements in such position, said locking means including locking plungers guided in bores on said guiding elements respectively for movement into and out of locking position.

3. In a drill steel guide, a support, a pair of cooperating guide arms pivotally mounted on said support to swing into and out of steel guiding position, and means for separately or simultaneously locking said arms in steel guiding position including locking means, one individual

to each arm, and each including a locking element mounted on an arm for movement with respect thereto into and out of locking position.

4. In a drill steel guide, a support, a pair of cooperating guide arms pivotally mounted on said support for independent movement into and out of steel guiding position, a latch pivotally mounted on said support and engageable with one or both of said arms for locking the latter in steel guiding position, and latch-release elements, one individual to each arm, mounted on said arms respectively, to move relative thereto for effecting release of said latch from engagement with said arms.

15 5. In a drill steel guide, a support having locking projections, a pair of cooperating guide arms pivotally mounted on said support for independent movement toward and from one another into and out of steel guiding position, and locking plungers, one individual to each arm, guided on said arms respectively and engageable with said locking projections of said support for separately locking said arms to said support.

20 6. In a drill steel guide, a support, a pair of cooperating guide arms pivotally mounted on said support for independent movement toward and from one another into and out of steel guiding position, and locking plungers, one individual to each arm, guided on said arms respectively and having locking lugs receivable in locking slots on said support for separately locking said arms to said support.

25 7. In a rock drill, a supporting guide along which a drill steel actuator is guided for movement, a support attached to the front end of said guide, a pair of guiding elements mounted on said support for independent movement into and out of steel guiding position, and locking devices including locking elements, one individual to each guiding element, guided on said guiding elements respectively for movement relative thereto and engageable with said support for separately locking said guiding elements in steel guiding position, said drill steel actuator as it moves forwardly along said guide being engageable with said locking elements to effect movement thereof relative to said guiding elements to release the latter for movement out of their guiding position.

30 8. In a rock drill, a supporting guide along which a drill steel actuator is guided for movement, a support attached to the front end of said guide, a pair of guiding elements mounted on said support for independent movement into and out of steel guiding position, locking devices including locking elements, one individual to each guiding element, guided on said guiding elements respectively, for movement relative thereto and engageable with said support for separately locking said guiding elements in steel guiding position, said drill steel actuator as it moves forwardly along said guide being engageable with said locking elements to effect movement thereof relative to said guiding elements to release the latter for movement out of their guiding position, and constantly acting means for automatically moving said guiding elements into their released non-guiding position when said locking devices are released.

35 9. In a drill steel guide, a support, cooperating guiding elements mounted on said support for relative movement into and out of steel guiding position, and means for separately locking said guiding elements to said support to hold the same in steel guiding position including lock-

ing plungers guided on said guiding elements respectively for movement into and out of locking position, one plunger individual to each of said guiding elements.

10. In a drill steel guide, a support, a pair of cooperating guide arms pivotally mounted on said support and swingable about their pivots into and out of steel guiding position, and means for locking said arms to said support to hold the same in steel guiding position, said locking means including a latch pivotally mounted on said support at the front side thereof and engageable with said guide arms.

11. In a drill steel guide, a support, a pair of cooperating guide arms pivotally mounted on said support and swingable about their pivots into and out of steel guiding position, and means for locking said arms to said support to hold the same in steel guiding position, said locking means including a latch pivotally mounted on said support at the front side thereof and engageable with said guide arms, and plungers guided on said arms respectively for effecting release of said latch.

12. In a drill steel guide, a support, a pair of cooperating guide arms pivotally mounted on said support and swingable about their pivots into and out of steel guiding position, and locking plungers guided on said arms respectively and having notches for receiving projections on said support for locking said arms in steel guiding position to said support.

13. In a drill steel guide, a support, a pair of cooperating guide arms pivotally mounted on said support to swing toward and from one another, and locking plungers, one individual to each arm, mounted on said guide arms respectively, for movement relative thereto and engageable with said support for separately locking said arms in steel guiding position.

14. In a rock drill, a supporting guide along which a drill steel actuator is guided for movement, a pair of cooperating guide arms pivotally mounted on said supporting guide, and locking devices including locking elements carried by said arms respectively, and each movable relative to the arm by which it is carried for locking said arms in steel guiding position, said drill steel actuator as it moves forwardly along said guide being engageable with said elements of said locking devices to move the same into unlocking position for effecting release of said guide arms.

15. In a drill steel guide, a support, a guide arm pivotally mounted on said support to swing relative thereto into and out of steel guiding position, and means for locking said arm against swinging movement in steel guiding position to said support, said locking means including a locking plunger supported by and guided on said arm and movable relative to said arm into locking engagement with said support, said locking plunger being movable relative to said arm out of locking engagement with said support to

free said arm for swinging movement, and said plunger being swingable with said arm out of guiding relation with the steel.

16. In a drill steel guide, a support, guiding elements mounted on said support for movement into and out of steel guiding position, locking means movable relative to said guiding elements for connecting said elements to said support, said guiding elements disposable separately or concurrently in guiding relation with a drill steel and said locking means serving to hold either or both of said elements in such relation, and means for effecting release by said locking means of the guiding element or elements held thereby including thrust exerting means guided for reciprocatory movement on each of said guiding elements and each operative when moved forwardly a predetermined distance relative to the guiding element on which it is guided to effect release of the latter for lateral movement out of guiding relation to the drill steel.

17. In a drill steel guide, a support, guiding elements mounted on said support for movement into and out of steel guiding position, locking means for connecting said elements to said support, said guiding elements disposable separately or concurrently in guiding relation with a drill steel and said locking means serving to hold either or both of said elements in such relation, said locking means including two pairs of cooperating surfaces, one pair individual to each guiding element, the locking surfaces of each pair having locking engagement along planes substantially parallel to the axis of the drill steel, one surface of each pair being movable laterally with a guiding element and the other surface of each pair being fixed against lateral movement relative to the support, and the surfaces of each pair being engageable in guiding-element-holding relation by relative movement longitudinally of the support in one direction and releasable to free the respective guiding elements by opposite longitudinal relative movement, and means carried by each guiding element and movable relative to it for effecting release between the surfaces which are operative to hold said element.

18. In a drill steel guide, a support, cooperating steel guiding elements mounted on said support for independent movement into and out of guiding relation with a drill steel to be guided, and means for separately or simultaneously locking said steel guiding elements against movement with respect to said support when said guiding elements are in steel guiding position, said locking means including lock actuating elements movably carried by said guiding elements respectively, said lock actuating elements being movable relative to said guiding elements to effect unlocking of said guiding elements to free the latter for movement out of steel guiding position relative to said support.

ELMER G. GARTIN.
